BREAD SLICING MACHINE SHARPENING MEANS
Herbert E. Boitscha, Bettendorf, Iowa, assignor to Bettendorf Bakery Equipment Co., Bettendorf, Iowa, a corporation of Iowa

Filed Apr. 7, 1960, Ser. No. 20,748
10 Claims. (Cl. 51—249)

This invention relates to honing or sharpening devices for slicing machines of the type having a plurality of endless slicing bands turning on and reaching between upper and lower drums or rolls.

In such slicing machines, the two reaches of each band between the drums frequently have a twist of 180 degrees but in any event are so arranged that the endless bands constitute a series of loops in surrounding relationship with each of the drums or rolls.

The invention contemplates the provision of a pair of cylindrical abrading members in association with the base frame of a bread slicing machine of the endless band type with one of such cylindrical abrading members being mounted for movement into and out of abrading engagement with one side of one edge of each of the endless bands, with the loops formed by such bands being in surrounding relationship with such cylindrical abrading member. The other of the cylindrical abrading members is mounted for movement into and out of abrading engagement with the same edge of the bands but on the opposite side of such same edge, and such other cylindrical abrading member is not surrounded by the loops formed by such bands but rather is excluded by such loops.

Endless blade band machines of the type to which the invention relates have been provided in which disassembly of the machines or complete removal of the drums under which the blade band pass is not required. An object of the present invention is to provide for the sharpening of the endless bands in such machines on both sides of the cutting edge of each band by cylindrical abrading members mounted for movement into and out of abrading engagement as stated above. Since the two cylindrical abrading members must respectively engage opposite sides of the cutting edge of each band, the topological relationship between the bands and abrading members is such that one of the abrading members must be included within the loops formed by the bands, although the other abrading member is excluded from the loops. The present invention provides for association of a pair of such abrading members with an endless blade band slicing machine in such a manner that blades may be removed from the machine without interference even with the loop-included cylindrical abrading member, whereby the band blades may be removed for repair or replacement without disassembling or removing any of the sharpening apparatus associated with the machine. This is of advantage as compared to the most closely related apparatus of the prior art because the present invention eliminates any necessity for removal and subsequent re-installation of the sharpening apparatus. Also the present invention eliminates the necessity for subsequent rechecking and readjustment of the re-installed sharpening apparatus.

It has previously been proposed to mount a series or pair of abrading members in an endless band blade slicing machine for movement into and out of sharpening association with the cutting edge of the band blades and to provide for reciprocating motion of the abrading members while in sharpening contact with the blades. An object of the present invention is to accomplish the engagement and disengagement of the abrading members together with the reciprocating motion of such members by an improved and simplified mechanical arrangement which is self-con-

2

tained in each sharpener assembly associated with each abrading member.

More particularly an object of the invention is to provide for mounting of the abrading member of a sharpener assembly so that oscillatory motion of the abrading member into and out of contact with the band blades is the function of the reciprocating motion of the abrading member back and forth transversely of the array of band blades so that as each abrading member is reciprocated it brings itself into engagement with the blades to be drawn thereacross in sharpening relationship therewith and then removes itself from such contact, all this being accomplished by means which are self-contained in each sharpener assembly so that the mechanical operations of the two sharpener assemblies are independent from each other.

These and other objects and advantages of the invention will be more fully understood from the following description of an example of the invention as employed in the currently widely used 180-degree twist type of slicing machine.

In the drawings:

FIGURE 1 is a side elevation of a band blade bread slicing machine in which the invention is employed.

FIGURE 2 is an enlarged view showing the upper right portion of FIGURE 1.

FIGURE 3 is a fragmentary view on a greatly enlarged scale taken from the plane of line 3—3 in FIGURE 2.

FIGURE 4 is a view of one of the sharpener assemblies taken from the plane of line 4—4 in FIGURE 2.

FIGURE 5 is a view taken from the plane of line 5—5 in FIGURE 4.

FIGURE 6 is a view taken from the plane of line 6—6 in FIGURE 5.

FIGURE 7 is a view taken from the plane of line 7—7 in FIGURE 5.

FIGURE 8 is a view taken from the plane of line 8—8 in FIGURE 2.

FIGURE 9 is a view similar to the lower right hand portion of FIGURE 8 showing the parts in an alternate position.

FIGURE 10 is a view taken from the plane of line 10—10 in FIGURE 4.

FIGURE 11 is a view similar to FIGURE 10 showing the parts in an alternate position.

FIGURE 12 is a view taken from the plane of line 12—12 in FIGURE 11.

FIGURE 13 is a schematic illustration of a control system for the illustrated sharpening apparatus.

In order to facilitate and condense description of the invention, the following discussion of the drawings will specify reference numerals for the various parts and in parentheses will specify by number the figure or figures of the drawings in which such reference numerals may most readily be found. For example, "abrading member 50 (2—4, 8, 10, 11)" signifies that the particular part referred to is given the reference numeral 50 and is to be conveniently found in FIGURES 2, 3, 4, 8, 10 and 11.

The base frame of the apparatus illustrated in the drawings is indicated generally by the reference numeral 10 (1, 2, 8, 9). First and second spaced apart rotatable drums 11 (1, 2, 8, 9) and 12 (1) are carried by the frame 10.

Endless slicing blades 15 (1—3, 8, 9) turn on and reach between the first and second drums 10 and 11, the slicing bands each having a cutting edge 16 (3, 8). The slicing bands 15 each have first and second reaches, both of which extend from a position in contact with and tangent to the first drum 11 to a position in contact with and tangent to the second drum 12. In the illustrated example, each of the first and second reaches has a twist of 180 degrees therein. The endless bands 15 therefor

constitute a series of twisted loops in surrounding relationship with each of the rolls 11 and 12.

In the illustrated apparatus the drum 11 is provided at one end with a non-rotating hub 20 (8) and is further provided with a bearing 21 operatively located between the hub 20 and the remainder of the drum. The hub 20 has formed therein a stub-shaft-receiving socket 22. A stub shaft 23 is provided in supported relationship with the base frame 10. The stub shaft is threaded in its support and has a head portion 32 which is adapted to be engaged by a wrench or crank, whereby the stub shaft may be backed out of the socket 22 and to a position of spaced relationship with the hub 20, as shown in FIGURE 8. Desirably the stub shaft 23 may be threaded engaged in a screw-positioned casting 24. The casting 24 is adapted to be adjusted in position with respect to a slideway 25 formed in or integrally affixed to the base frame 10, such adjustment being effected by a frame-mounted adjusting screw 26. The opposite end of the upper drum 11 may be provided with a similar arrangement adapted to be raised and lowered by an adjusting screw 27. The arrangement at the right hand end of the drum 11 as viewed in FIGURE 8 is similar in most respects to that at the left hand end with the exception, as shown, that the shaft 28 at the right hand end corresponding to the shaft 23 at the left hand end need not be threaded for backing out from its associated hub 29. The adjusting screws 26 and 27 may be turned to shift the groove or sliding member 24 and its counterpart on the opposite end of the drum 11 in order to slightly raise or lower the drum 11 and therefore adjust blade tension or remove all tension. However it will be understood that through such adjusting screws 26 the upper drum 11 is carried by the frame structure of the machine through the hubs 22 and 29.

In the illustrated example of the invention, there are provided first and second sharpener assemblies indicated respectively by the reference numerals 35 (1, 2, 8) and 36 (1, 2, 4, 5). The first and second sharpener assemblies are identical in many respects and all of the identical elements thereof are indicated by like reference numerals.

Each sharpener assembly 35 and 36 includes a sharpener carriage comprising a tubular structure including a sleeve member 40 (4, 6-9) and a relatively short sleeve member 41 joined by a casting 42 (6). The sharpener carriages are adapted to reciprocate with respect to the base frame in a direction parallel to the axes of the band blade drums 11 and 12 and are adapted to oscillate in planes normal to the axes of the drums. To this end, each sharpener carriage receives a shaft 45 (1, 2, 4-9) extending parallel to the axes of the drums 11 and 12. The shaft 45 associated with the first sharpener assembly 35 extends through the loops formed by the endless blade bands 15 whereby the loops are in surrounding relationship with such shaft and, as will become clear below, with the sharpener carriage carried thereon. The shaft 45 associated with the second sharpener assembly 36 also extends parallel to the axes of the drums 11 and 12 but extends exteriorly to the loops formed by the band blades, so that the loops are in excluding relationship with such shaft 45 and the sharpener carriage carried thereon.

At opposite ends of the tubular structure comprising the sleeves 40 and 41 are a pair of end members which form part of the sharpener carriage and which are designated by the reference numerals 48 (4) and 49 (4, 5). Rotatably mounted on such members 48 and 49 is a cylindrical abrading member 50 (2-4, 8, 10, 11) which may comprise a series of cylindrical sections 51 supported on a shaft 52 (4) which is rotatably mounted in bearings supported in the members 48 and 49. It will thus be seen that the cylindrical abrading member 50 is mounted on a sharpener carriage and reciprocates and oscillates bodily with the sharpener carriage. The recip-

rocation occurs lengthwise along the direction of the shaft 45 and therefore parallel to the axes of the blade drums 11 and 12. The oscillation occurs around the axis of the shaft 45. Such oscillatory movement of each abrading member 50 bodily with its sharpener carriage about its associated shaft 45 accomplishes movement of the abrading member 50 into and out of engagement with one side of one edge of the blade bands 15, as illustrated perhaps most clearly in FIGURE 2 where each of the abrading members 50 is shown in blade-engaging position and in which the position of each abrading member when it is lifted out of engagement with the blade bands is also indicated in phantom view.

Reciprocating-drive-linkage means is provided for reciprocating each sharpener carriage back and forth along its associated shaft 45. Such reciprocating-drive-linkage means comprises a shaft 59 (6, 9) rotatably carried in the body of casting 42. Fixed at an end of the shaft 58 is a travel cam 59 which drivingly engages the guide plates 60 and 61 which are fixed to the shaft 45. The shaft 45 is fixed to the frame 10. It will therefore be apparent that as the shaft 48 rotates, the travel cam 59 is contained between the guide plates 60 and 61 causing the sharpener carriage including the sleeves 40 and 41 and the body 42 therebetween and also the end members 48 and 49 and the abrading member 50 therebetween to reciprocate transversely of the plates, one back and forth reciprocation being completed for each rotation of the shaft 58.

30 A motor 63 (1, 2, 4, 5, 7) is provided on each of the sharpener assemblies in driving association with the cylindrical abrading member 50 for powering its rotation. This drive is accomplished through the belt 65 (4, 5), a suitable sheave 66 (4, 5) being provided in association 35 with the shaft 52 of the abrading member 50. The motor 63 is also in driving association with the carriage reciprocating linkage described above, since the motor shaft 67 (6, 7) is linked through a worm to a gear 68 keyed to the shaft 58.

40 According to the invention camming means is provided for imposing the oscillatory motion of the abrading member about the associated shaft 45 as a function of the reciprocating motion of the abrading member back and forth parallel to the shaft 45. For each sharpener assembly, such camming means comprises a cam plate 70 (4, 10-12) tied to a block 71 which, in turn, is rigidly fixed to the shaft 45, and a cam follower wheel 73 which is mounted on the member 48. As may be seen most clearly in FIGURE 2, the relationship of the parts is such that the relatively great weight of the abrading member 50 and its associated shaft tends to move the sharpener carriage associated with each sharpener assembly 35 and 36 in the clockwise direction as viewed in FIGURE 2 to thereby engage the abrading members 50 with the blades 15. When the blades are engaged, the cam 70 and cam follower 73 have the relationship shown in FIGURE 10, and the sharpener carriage as a whole is in the position shown in FIGURE 8. When the associated sharpener carriage is reciprocated to the opposite extreme from that shown in FIGURES 8 and 10, the relationship of the parts is that illustrated in FIGURES 9 and 11. Engagement of the cam follower wheel 73 with the camming surface 75 during such reciprocating motion from right to left, as viewed in FIGURES 8-11, causes the carriages to move in the counterclockwise direction as viewed in FIGURE 2. This removes the abrading members 50 from engagement with the blades 15. Blade-engaging position corresponding to FIGURES 8 and 10 is shown in phantom lines in FIGURE 12 and the fully raised position corresponding to FIGURES 9 and 11 is shown in solid lines in FIGURE 12.

70 It will thus be seen that in at least one point during the full range of reciprocatory travel of each abrading member, it is in blade-disengaging oscillatory position. Such 75 at least one point at which the abrading member is in

blade-disengaging oscillatory position is at one end of the reciprocatory travel of the abrading member.

The means mounting the sharpener carriage associated with the first sharpener assembly 35 includes first and second bracket members 81 and 82 (2, 8). The means mounting the sharpener carriage associated with the second sharpener assembly 36 includes third and fourth bracket members 83 (4) and 84 (2, 4).

The first bracket member 81 includes one end portion 86 which defines a socket or bore for receiving its associated shaft 45 and includes another end portion 87 which defines a bore for receiving the hub 20. The end portions 86 and 87 are displaced from each other with respect to the axial direction of the drum 11 and are also displaced from each other in a direction normal to such axis, that is in a radial direction with respect to the drum 11. The end portions 86 and 87 are joined by an intermediate arm portion 88.

It will be understood that the first bracket member 81 ties its associated end of the shaft 45 to the base frame 10 solely through the hub 20 so that upon removal of the stub shaft 23 from the stub-shaft-receiving socket of the hub 20 the blades 15 may be removed from the rolls or drums without demounting the bracket members. This is accomplished by bringing the blades 15 off the end of the drum 11 and then between the frame structure 10 and the left end of the roll 11 downwardly past the now-retracted stub shaft 23 and outwardly immediately above the intermediate arm portion 88.

The second bracket member 82 may be fixed to the casting 30 (2, 8) which corresponds to the casting 24 and which is rigidly supported on the frame assembly 10 and tied thereto through the adjusting screws 27 whereby the shaft 45 associated with the first sharpener assembly 35 and the sharpener carriage which is supported on such shaft 45 moves bodily slightly up and down in parallelism to the axes of the drum 11 as the screws 26 and 27 are turned to adjust the tension of the band blades, or to remove all tension so that the band blades may readily slide over the drum 11 as for removal and replacement.

The third and fourth bracket members 83 and 84 are simply bolted to the frame members 10 as illustrated in FIGURE 2.

Near that end of each shaft 45 which is associated with the bracket 82 or the bracket 84 there is provided an axially extending finger 90 (2, 4) which is rigidly supported on a collar 91 (4) fixed to the associated shaft 45.

Each of the brackets 82 and 84 is provided with a rigidly affixed yoke portion 92 (2) having set screws 93 adapted to bear on opposite sides of the associated finger 90. By tightening one set screw 93 and backing off the other set screw 93 of each yoke 92, the angular position of the associated shaft 45 with respect to the frame structure may be adjusted to vary the angular position of each cam plate 70 and thereby adjust the datum oscillatory positions of the sharpener carriage structure and the abrading member carried bodily therewith.

In the illustrated structure the shaft 58 is provided at its outer end with a control cam 100 (6, 7) which is adapted to engage and open a microswitch 101 (5, 7) upon each complete revolution of the shaft 58. There is also provided a solenoid 103 (4, 5) and a spring-engaged brake 104 both of which are mounted on the member 49. Actuation of the solenoid 103 is adapted to release the brake 104 by overcoming the bias of the spring 105. Under biasing of the spring 105, the brake 104 normally operates to brake rotation of the abrading members 50 and the shaft 52 and thereby to brake rotation of the motor 63.

The control arrangement may be as schematically illustrated in FIGURE 13. Upon engagement of a starting button or switch 110 a circuit is completed through the relay 111 closing the switches 112 to energize the motor 63 and the solenoid 103. Energizing the solenoid 103 disengages the brake and allows the motor to drive the structure through one cycle of operation. When the

control cam 100 disengages the switch 101 allowing such switch to close, the starting button 110 may be released and the circuit, through the relay 111, will be maintained by the switch 101 until a single rotation of the shaft 58 is completed whereupon the control cam 100 will re-engage and open the switch 101 to thereby break the circuit through the relay 111. Thereupon the switch 112 will open and the brake 104 will be activated by the spring 105 bringing the now-de-energized motor 63 to a quick stop.

The switch 110 may be of a time delay type so that when it is closed at the beginning of a cycle to energize the relay 111 and close the switches 112, it will not open until a sufficient time has elapsed to allow the cam 100 to pass out of engagement with the switch 101. This allows the starting switch 110 to be immediately released by the operator after it is first closed to start the cycle, without waiting for the switch 101 to close.

The stop switch 109 may be opened at any time to stop the apparatus in its cycle of operation, as for purposes of adjustment or the like. Upon opening the switch 109, the switch 112 will open to de-energize the motor 63 and the solenoid 103 to quickly stop the apparatus. When the switch 112 is open the apparatus will remain stopped even through the switch 109 may now be reclosed and the apparatus will remain stopped until the starting switch 110 is again momentarily closed to energize the relay 111 and close the switch 112, whereupon the apparatus continues its cycle of operation until the control cam 100 opens the switch 101 to de-energize the relay 111 and open the switches 112 and thereby stop the apparatus at the conclusion of its cycle of operations. At such conclusion of such cycle of operations, the cam follower wheels 73 will be in the position shown in FIGURE 11-35 and the abrading members 50 will be in blade-disengaging position.

The control system shown in FIGURE 13 may be duplicated for each of the blade sharpener assemblies 35 and 36 or alternatively the motor and brake solenoids 40 of both sharpeners may be controlled from a single set of start and stop switches by separate relays 111 and switch sets 112.

The illustrated control systems are adapted to be actuated manually by an operator. If desired, the operator may be prompted to actuate the sharpening apparatus by means entirely independent of the sharpener apparatus, such as a red light or other visible signal or an audible signal or other indication that a given interval of machine operating time has elapsed since the most recent sharpening operation. For bread slicing machines operating on a commercial basis, the intervals between sharpening of the blades may typically be in the neighborhood of from two to four hours. Accordingly, there may be provided a timing light adapted to flash at the desired intervals to remind the operator to sharpen the machine. The timer for the light may be connected to the power supply for the blade sharpening machine so that the machine is automatically shut down until the timer is reset by the operator after the sharpening operation.

Another alternative is to provide a timer for automatically closing the start switch 110 at desired intervals to thereby provide for fully automatic operation of the blade sharpener apparatus.

The invention is not restricted to the slavish imitation of each and every one of the details described above which have been set forth merely by way of example with the intent of most clearly setting forth the teaching of the invention. Obviously devices may be provided which change, eliminate or add certain specific structural details without departing from the invention.

What is claimed is:

1. The combination with a base frame, first and second parallel spaced apart rotatable drums carried by said frame, at least one of said drums having a non-rotating hub, a bearing between said hub and the remainder of

said one drum, a stub-shaft-receiving socket formed in said hub, a stub shaft in supported association with said base frame, said stub shaft being received in removable relationship in said socket, endless slicing bands turning on and reaching between said first and second drums, said slicing bands each having a cutting edge and said slicing bands each having first and second reaches both of which extend from a position in contact with and tangent to said first drum to a position in contact with and tangent to said second drum, said endless bands therefor constituting a series of loops in surrounding relationship with each of said rolls, of: a first sharpener assembly including a sharpener carriage, means mounting said sharpener carriage on said base frame for reciprocation in a given direction transversely of said bands and for oscillation in planes normal to said direction, said given direction being parallel to the axes of said drums, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, reciprocating-drive-linkage means for reciprocating said sharpener carriage, motor means in driving association with said cylindrical abrading member for powering the rotation thereof relative to said sharpener carriage and in driving association with said carriage-reciprocating linkage means for actuation thereof, said means mounting said sharpener carriage on said base frame comprising a shaft extending parallel to the axes of said drums and extending through said loops whereby said loops are in surrounding relationship with said shaft and said sharpener carriage carried thereon, first and second bracket members at opposite ends of said shaft for tying said shaft to said base frame, one of said first and second bracket members tying its associated end of said shaft to said base frame solely through said hub whereby upon removal of said hub from said stub-shaft-receiving socket of said hub said blades may be removed from said rolls without demounting of said bracket members, shaft and sharpener carriage, and a second sharpener assembly including a second cylindrical abrading member with which said loops are in excluding relationship, said second abrading member being movable into and out of abrading engagement with the aforesaid one edge of said bands on the side thereof other than the aforesaid one side.

2. The combination with a base frame, first and second parallel spaced apart rotatable drums carried by said frame, at least one of said drums having a non-rotating hub, a bearing between said hub and the remainder of said one drum, a stub-shaft-receiving socket formed in said hub, a stub shaft in supported association with said base frame, said stub shaft being received in removable relationship in said socket, endless slicing bands turning on and reaching between said first and second drums, said slicing bands each having a cutting edge and said slicing bands each having first and second reaches both of which extend from a position in contact with and tangent to said first drum to a position in contact with and tangent to said second drum, said endless bands therefor constituting a series of loops in surrounding relationship with each of said rolls, of: a first sharpener assembly including a sharpener carriage, means mounting said sharpener carriage on said base frame for reciprocation in a given direction transversely of said bands and for oscillation in planes normal to said direction, said given direction being parallel to the axes of said drums, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage ac-

complishing movement of said abrading member into and out of engagement with one side of one edge of said bands, reciprocating-drive-linkage means for reciprocating said sharpener carriage, motor means in driving association with said cylindrical abrading member for powering the rotation thereof relative to said sharpener carriage and in driving association with said carriage-reciprocating linkage means for actuation thereof, said means mounting said sharpener carriage on said base frame comprising a shaft extending parallel to the axes of said drums and extending through said loops whereby said loops are in surrounding relationship with said shaft and said sharpener carriage carried thereon, first and second bracket members at opposite ends of said shaft for tying said shaft to said base frame, one of said first and second bracket members tying its associated end of said shaft to said base frame solely through said hub whereby upon removal of said hub from said stub-shaft-receiving socket of said hub said blades may be removed from said rolls without demounting of said bracket members, shaft and sharpener carriage, a second sharpener assembly including a second sharpener carriage, second mounting means mounting said second sharpener carriage on said base frame for reciprocation in said given direction transversely of said bands and for oscillation in planes normal to said direction, a second cylindrical abrading member rotatably mounted on said second sharpener carriage for reciprocation and oscillation bodily therewith and for rotation relative thereto about an axis parallel to said given direction, said oscillatory motion of said second abrading member bodily with said second sharpener carriage accomplishing movement of said second abrading member into and out of abrading engagement with the aforesaid one edge of said bands on the side thereof other than the aforesaid one side, second reciprocating-drive-linkage means for reciprocating said second sharpener carriage, second motor means in driving association with said second cylindrical abrading member for powering the rotation thereof relative to said second sharpener carriage and in driving association with said second carriage-reciprocating linkage means for actuation thereof, said second mounting means comprising a second shaft extending parallel to the axes of said drums and extending exteriorly to said loops whereby said loops are in excluding relationship with said second shaft and said second sharpener carriage carried thereon, third and fourth bracket members at opposite ends of said second shaft for tying said second shaft to said base frame.

3. The combination with a base frame, first and second parallel spaced apart rotatable drums carried by said frame, at least one of said drums having a non-rotating hub, a bearing between said hub and the remainder of said one drum, a stub-shaft-receiving socket formed in said hub, a stub shaft in supported association with said base frame, said stub shaft being received in removable relationship in said socket, endless slicing bands turning on and reaching between said first and second drums, said slicing bands each having a cutting edge and said slicing bands each having first and second reaches both of which extend from a position in contact with and tangent to said first drum to a position in contact with and tangent to said second drum, said endless bands therefor constituting a series of loops in surrounding relationship with each of said rolls, of: a first sharpener assembly including a sharpener carriage, means mounting said sharpener carriage on said base frame for reciprocation in a given direction transversely of said bands and for oscillation in planes normal to said direction, said given direction being parallel to the axes of said drums, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into

and out of engagement with one side of one edge of said bands, reciprocating-drive-linkage means for reciprocating said sharpener carriage, motor means in driving association with said cylindrical abrading member for powering the rotation thereof relative to said sharpener carriage and in driving association with said carriage-reciprocating linkage means for actuation thereof, camming means for imposing said oscillatory motion of said abrading member as a function of the reciprocatory motion of said abrading member with said abrading member being in blade-disengaging oscillatory position at at least one point in its reciprocatory travel and in blade-engaging oscillatory position throughout a major portion of its reciprocatory travel, said means mounting said sharpener carriage on said base frame comprising a shaft extending parallel to the axes of said drums and extending through said loops whereby said loops are in surrounding relationship with said shaft and said sharpener carriage carried thereon, first and second bracket members at opposite ends of said shaft for tying said shaft to said base frame, one of said first and second bracket members tying its associated end of said shaft to said base frame solely through said hub whereby upon removal of said stub shaft from said stub-shaft-receiving socket of said hub said blades may be removed from said rolls without demounting of said bracket members, shaft and sharpener carriage, and a second sharpener assembly including a second cylindrical abrading member with which said loops are in excluding relationship, said second abrading member being movable into and out of abrading engagement with the aforesaid one edge of said bands on the side thereof other than the aforesaid one side.

4. The combination with a base frame, first and second parallel spaced apart rotatable drums carried by said frame, at least one of said drums having a non-rotating hub, a bearing between said hub and the remainder of said one drum, a stub-shaft-receiving socket formed in said hub, a stub shaft in supported association with said base frame, said stub shaft being received in removable relationship in said socket, endless slicing bands turning on and reaching between said first and second drums, said slicing bands each having a cutting edge and said slicing bands each having first and second reaches both of which extend from a position in contact with and tangent to said first drum to a position in contact with and tangent to said second drum, said endless bands therefor constituting a series of loops in surrounding relationship with each of said rolls, of: a first sharpener assembly including a sharpener carriage, means mounting said sharpener carriage on said base frame for reciprocation in a given direction transversely of said bands and for oscillation in planes normal to said direction, said given direction being parallel to the axes of said drums, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, reciprocating-drive-linkage means for reciprocating said sharpener carriage, motor means in driving association with said cylindrical abrading member for powering the rotation thereof relative to said sharpener carriage and in driving association with said carriage-reciprocating linkage means for actuation thereof, camming means for imposing said oscillatory motion of said abrading member as a function of the reciprocatory motion of said abrading member with said abrading member being in blade-disengaging oscillatory position at at least one point in its reciprocatory travel and in blade-engaging oscillatory position throughout a major portion of its reciprocatory travel, said at least one point at which said abrading member is in blade-disengaging oscillatory position being at one end of its reciprocatory travel, said means mounting said sharpener 7

carriage on said base frame comprising a shaft extending parallel to the axes of said drums and extending through said loops whereby said loops are in surrounding relationship with said shaft and said sharpener carriage carried thereon, first and second bracket members at opposite ends of said shaft for tying said shaft to said base frame, one of said first and second bracket members tying its associated end of said shaft to said base frame solely through said hub whereby upon removal of said stub shaft from said stub-shaft-receiving socket of said hub said blades may be removed from rolls without demounting of said bracket members, shaft and sharpener carriage, and a second sharpener assembly including a second cylindrical abrading member with which said loops are in excluding relationship, said second abrading member being movable into and out of abrading engagement with the aforesaid one edge of said bands on the side thereof other than the aforesaid one side.

5. The combination with a base frame, first and second parallel, spaced-apart drums rotatably mounted on said base frame, and endless slicing bands turning on and reaching between said first and second drums, said slicing bands each having a cutting edge and said slicing bands each having first and second reaches both of which extend from a position in contact with and tangent to said first drum to a position in contact with and tangent to said second drum, of: a sharpener carriage, means mounting said sharpener carriage on said base frame for reciprocation in a given direction transversely of said bands and for oscillation in planes normal to said direction, said given direction being parallel to the axes of said drums; a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, linkage means for reciprocating said sharpener carriage, motor means in driving association with said cylindrical abrading member for powering the rotation thereof relative to said sharpener carriage and in driving association with said carriage-reciprocating linkage means for actuation thereof, camming means for imposing said oscillatory motion of said abrading member as a function of the reciprocatory motion of said abrading member with said abrading member being in blade-disengaging oscillatory position at at least one point in its reciprocatory travel and in blade-engaging oscillatory position throughout a major portion of its reciprocatory travel, and a second sharpener assembly including a second cylindrical abrading member with which said loops are in excluding relationship, said second abrading member being movable into and out of abrading engagement with the aforesaid one edge of said bands on the side thereof other than the aforesaid one side.

6. The combination with a base frame, first and second parallel, spaced-apart drums rotatably mounted on said base frame, and endless slicing bands turning on and reaching between said first and second drums, said slicing bands each having a cutting edge and said slicing bands each having first and second reaches both of which extend from a position in contact with and tangent to said first drum to a position in contact with and tangent to said second drum, of: a sharpener carriage, means mounting said sharpener carriage on said base frame for reciprocation in a given direction transversely of said bands and for oscillation in planes normal to said direction, said given direction being parallel to the axes of said drums; a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, linkage means for reciprocating said sharpener carriage, motor means in driving association with said cylindrical abrading member for powering the rotation thereof relative to said sharpener carriage and in driving association with said carriage-reciprocating linkage means for actuation thereof, camming means for imposing said oscillatory motion of said abrading member as a function of the reciprocatory motion of said abrading member with said abrading member being in blade-disengaging oscillatory position at at least one point in its reciprocatory travel and in blade-engaging oscillatory position throughout a major portion of its reciprocatory travel, and a second sharpener assembly including a second cylindrical abrading member with which said loops are in excluding relationship, said second abrading member being movable into and out of abrading engagement with the aforesaid one edge of said bands on the side thereof other than the aforesaid one side.

6. The combination with a base frame, first and second parallel, spaced-apart drums rotatably mounted on said base frame, and endless slicing bands turning on and reaching between said first and second drums, said slicing bands each having a cutting edge and said slicing bands each having first and second reaches both of which extend from a position in contact with and tangent to said first drum to a position in contact with and tangent to said second drum, of: a sharpener carriage, means mounting said sharpener carriage on said base frame for reciprocation in a given direction transversely of said bands and for oscillation in planes normal to said direction, said given direction being parallel to the axes of said drums, 70 a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading mem-

her into and out of engagement with one side of one edge of said bands, linkage means for reciprocating said sharpener carriage, motor means in driving association with said cylindrical abrading member for powering the rotation thereof relative to said sharpener carriage and in driving association with said carriage-reciprocating linkage means for actuation thereof, camming means for imposing said oscillatory motion of said abrading member as a function of the reciprocatory motion of said abrading member with said abrading member being in blade-disengaging oscillatory position at at least one point in its reciprocatory travel and in blade-engaging oscillatory position throughout a major portion of its reciprocatory travel, said at least one point at which said abrading member is in blade-disengaging oscillatory position being at one end of its reciprocatory travel, and a second sharpener assembly including a second cylindrical abrading member with which said loops are in excluding relationship, said second abrading member being movable into and out of abrading engagement with the aforesaid one edge of said bands on the side thereof other than the aforesaid one side.

7. In endless band bread slicing machines having sharpening means combined therewith in which the bands are removable without disassembly of the slicing machine and without demounting of the sharpening means, a base frame, first and second parallel spaced apart rotatable drums carried by said frame, at least one of said drums having a non-rotating hub, a bearing between said hub and the remainder of said one drum, a stub-shaft-receiving socket formed in said hub, a stub shaft in supported association with said base frame, said stub shaft being received in removable relationship in said socket, endless slicing bands turning on and reaching between said first and second drums, said slicing bands each having a cutting edge and said slicing bands each having first and second reaches both of which extend from a position in contact with and tangent to said first drum to a position in contact with and tangent to said second drum, said endless bands therefor constituting a series of loops in surrounding relationship with each of said rolls, first and second sharpener assemblies including first and second cylindrical abrading members each extending parallel to said drums, first mounting means mounting said first cylindrical abrading member for movement into and out of abrading engagement with one side of one edge of said bands with said loops in surrounding relationship with said first abrading member, second mounting means mounting said second cylindrical abrading member for movement into and out of abrading engagement with the aforesaid one edge of said bands on the side thereof other than the aforesaid one side with said loops in excluding relationship with said second abrading member, said first and second mounting means being tied to said base frame with one end of said first mounting means being tied to said base frame solely through said hub.

8. The combination with a base frame, first and second parallel spaced apart rotatable drums carried by said frame, at least one of said drums having a non-rotating hub, a bearing between said hub and the remainder of said one drum, a stub-shaft-receiving socket formed in said hub, a stub shaft in supported association with said base frame, said stub shaft being received in removable relationship in said socket, endless slicing bands turning on and reaching between said first and second drums, said slicing bands each having a cutting edge and said slicing bands each having first and second reaches both of which extend from a position in contact with and tangent to said first drum to a position in contact with and tangent to said second drum, said endless bands therefor constituting a series of loops in surrounding relationship with each of said rolls, of: a first sharpener assembly including a sharpener carriage, means mounting said sharpener carriage on said base frame for reciprocation in a given direction transversely of said bands and for oscillation in

planes normal to said direction, said given direction being parallel to the axes of said drums, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, reciprocating-drive-linkage means for reciprocating said sharpener carriage, motor means in driving association with said cylindrical abrading member for powering the rotation thereof relative to said sharpener carriage and in driving association with said carriage-reciprocating linkage means for actuation thereof, camming means for imposing said oscillatory motion of said abrading member as a function of the reciprocatory motion of said abrading member with said abrading member being in blade-disengaging oscillatory position at at least one point in its reciprocatory travel and in blade-engaging oscillatory position throughout a major portion of its reciprocatory travel, said at least one point at which said abrading member is in blade-disengaging oscillatory position being at one end of its reciprocatory travel, said means mounting said sharpener carriage on said base frame comprising a shaft extending parallel to the axes of said drums and extending through said loops whereby said loops are in surrounding relationship with said shaft and said sharpener carriage carried thereon, first and second bracket members at opposite ends of said shaft for tying said shaft to said base frame, one of said first and second bracket members tying its associated end of said shaft to said base frame solely through said hub whereby upon removal of said stub shaft from said stub-shaft-receiving socket of said hub said blades may be removed from rolls without demounting of said bracket members, shaft and sharpener carriage, and a second sharpener assembly including a second cylindrical abrading member with which said loops are in excluding relationship, said second abrading member being movable into and out of abrading engagement with the aforesaid one edge of said bands on the side thereof other than the aforesaid one side, said one of said first and second bracket members including an intermediate arm portion and also including at one end means for receiving said shaft and at said other end means for receiving said hub, said respective receiving means being displaced from each other with respect to said given direction and also in a direction normal to said given direction and being joined by said intermediate arm portion.

9. The combination with a base frame, first and second parallel spaced apart rotatable drums carried by said frame, at least one of said drums having a non-rotating hub, a bearing between said hub and the remainder of said one drum, a stub-shaft-receiving socket formed in said hub, a stub shaft in supported association with said base frame, said stub shaft being received in removable relationship in said socket, endless slicing bands turning on and reaching between said first and second drums, said slicing bands each having a cutting edge and said slicing bands each having first and second reaches both of which extend from a position in contact with and tangent to said first drum to a position in contact with and tangent to said second drum, said endless bands therefor constituting a series of loops in surrounding relationship with each of said rolls, of: a first sharpener assembly including a sharpener carriage, means mounting said sharpener carriage on said base frame for reciprocation in a given direction transversely of said bands and for oscillation in planes normal to said direction, said given direction being parallel to the axes of said drums, a cylindrical abrading member rotatably mounted on said sharpener carriage for reciprocation and oscillation bodily therewith and for rotation relative thereto about an axis parallel to said given direction, said oscillatory motion of said abrading

member bodily with said sharpener carriage accomplishing movement of said abrading member into and out of engagement with one side of one edge of said bands, reciprocating-drive-linkage means for reciprocating said sharpener carriage, motor means in driving association with said cylindrical abrading member for powering the rotation thereof relative to said sharpener carriage and in driving association with said carriage-reciprocating linkage means for actuation thereof, camming means for imposing said oscillatory motion of said abrading member as a function of the reciprocatory motion of said abrading member with said abrading member being in blade-disengaging oscillatory position at at least one point in its reciprocatory travel and in blade-engaging oscillatory position throughout a major portion of its reciprocatory travel, said means mounting said sharpener carriage on said base frame comprising a shaft extending parallel to the axes of said drums and extending through said loops whereby said loops are in surrounding relationship with said shaft and said sharpener carriage carried thereon, first and second bracket members at opposite ends of said shaft for tying said shaft to said base frame, one of said first and second bracket members tying its associated end of said shaft to said base frame solely through said hub whereby upon removal of said stub shaft from said stub-shaft-receiving socket of said hub said blades may be removed from said rolls without demounting of said bracket members, shaft and sharpener carriage, and a second sharpener assembly including a second cylindrical abrading member with which said loops are in excluding relationship, said second abrading member being movable into and out of abrading engagement with the aforesaid one edge of said bands on the side thereof other than the aforesaid one side, said one of said first and second bracket members including an intermediate arm portion and also including at one end means for receiving said shaft and at said other end means for receiving said hub, said respective receiving means being displaced from each other with respect to said given direction and also in a direction normal to said given direction and being joined by said intermediate arm portion.

10. The combination with a base frame, first and second parallel spaced apart rotatable drums carried by said frame, at least one of said drums having a non-rotating hub, a bearing between said hub and the remainder of said one drum, a stub-shaft-receiving socket formed in said hub, a stub shaft in supported association with said base frame, said stub shaft being received in removable relationship in said socket, endless slicing bands turning on and reaching between said first and second drums, said slicing bands each having a cutting edge and said slicing

bands each having first and second reaches both of which extend from a position in contact with and tangent to said first drum to a position in contact with and tangent to said second drum, said endless bands therefor constituting a series of loops in surrounding relationship with each of said rolls, of: a first sharpener assembly including a sharpener carriage, means mounting said sharpener carriage on said base frame for reciprocation in a given direction transversely of said bands and for oscillation in planes normal to said direction, said given direction being parallel to the axes of said drum, a cylindrical abrading member rotatably mounted on said sharpener carriage for reciprocation and oscillation bodily therewith and for rotation relative thereto about an axis parallel to said given direction, said oscillatory motion of said abrading member bodily with said sharpener carriage accomplishing movement of said abrading member into and out of engagement with one side of one edge of said bands, reciprocating-drive-linkage means for reciprocating said sharpener carriage, motor means in driving association with said cylindrical abrading member for powering the rotation thereof relative to said sharpener carriage and in driving association with said carriage-reciprocating linkage means for actuation thereof, said means mounting said sharpener carriage on said base frame comprising a shaft extending parallel to the axes of said drums and extending through said loops whereby said loops are in surrounding relationship with said shaft and said sharpener carriage carried thereon, first and second bracket members at opposite ends of said shaft for tying said shaft to said base frame, one of said first and second bracket members tying its associated end of said shaft to said base frame solely through said hub whereby upon removal of said stub shaft from said stub-shaft-receiving socket of said hub said blades may be removed from said rolls without demounting of said bracket members, shaft and sharpener carriage, and a second sharpener assembly including a second cylindrical abrading member with which said loops are in excluding relationship, said second abrading member being movable into and out of abrading engagement with the aforesaid one edge of said bands on the side thereof other than the aforesaid one side, said one of said first and second bracket members including an intermediate arm portion and also including at one end means for receiving said shaft and at said other end means for receiving said hub, said respective receiving means being displaced from each other with respect to said given direction and also in a direction normal to said given direction and being joined by said intermediate arm portion.
